UNITED STATES PATENT OFFICE.

CHARLES O. WIDMAYER, OF SYRACUSE, NEW YORK.

MOUTHPIECE FOR WIND MUSICAL INSTRUMENTS.

1,353,297.

Specification of Letters Patent. Patented Sept. 21, 1920.

Application filed May 16, 1919. Serial No. 297,662.

To all whom it may concern:

Be it known that I, CHARLES O. WIDMAYER, a citizen of the United States, and a resident of Syracuse, in the county of Onondaga and State of New York, have invented 5 a certain new and useful Mouthpiece for Wind Musical Instruments, of which the following is a specification.

This invention relates to mouth pieces for 10 wind musical instruments or instruments of the trumpet type as cornets, French horns, trombones, tubas, etc., and has for its object a particularly simple, efficient and durable appliance therefor whereby the tones can be 15 produced without the fatigue to the lips, etc., resulting from the ordinary way of playing these instruments. The invention consists in the novel features and in the combinations and constructions hereinafter set 20 forth and claimed.

In describing this invention, reference is had to the accompanying drawings in which like characters designate corresponding parts in all the views.

25 Figures 1 and 2 are respectively, lengthwise vertical and horizontal sectional views of a mouth piece provided with one form of my invention.

Fig. 3 is a vertical sectional view, similar 30 to Fig. 1 of another embodiment thereof.

Fig. 4 is a detail sectional view of another form thereof.

The mouth piece comprises, generally, a cup shaped body, or member, and a flexible 35 member extending lengthwise of the cavity of the body and secured at its inner end to the inner end of the cavity of the body and extending beyond the entrance of the mouth piece, said member curving toward one side 40 of the mouth piece, as the upper side. It may, however, curve in any other direction dependent on the position the mouth piece occupies relatively to the instrument. The term "upper side" herein and in the claims 45 is used for convenience and brevity. The flexible member is also compressible endwise.

In Figs. 1 and 2, 1 designates the mouth piece which includes a cup shaped body or member 2 and a hollow stem leading from 50 the apex or bottom of the cup-shaped body.

3 is the flexible member which comprises a leaf extending lengthwise of the cavity of the cup-shaped body or member 2 and out of the entrance of the mouth piece and curving upwardly toward its outer end. It divides the cavity of the mouth piece into up-

per and lower sections and is preferably located in the upper half of said cavity. Said leaf also, as seen in Fig. 2, conforms to the contour of the cavity but its side edges 60 are spaced apart from the wall of the cavity, forming air passages around the leaf.

The mouth piece is also compressible endwise, it being here shown as formed with transverse folds or plaits, 4, near its inner 65 end. The flexible member in addition to the leaf includes a hollow plug or sleeve 5 at its inner end, from a portion of which the leaf projects, this plug being inserted in the passage 6 of the stem and serving to support 70 the leaf.

In the form shown in Figs. 1 and 2, the player usually places his upper lip against the upper side of the mouth piece and the end of the leaf between the upper lip and the teeth and for the upper tones presses the leaf upwardly and inwardly and for lower tones allows it to return to its normal position. To facilitate the return thereof to its 75 normal position, a light spring 7 may be 80 provided, this spring being secured at 8 in the wall of the cavity and having its free end lightly engaging the upper face of the leaf.

In Fig. 3 the leaf 9 is shown as unprovided with folds and as bow-shaped and secured at its outer end to the entrance piece 10 which slides axially of the cup-shaped body against the action of a spring 11. During endwise movement of the entrance piece effected by the player pressing the instrument against the lips with varying force, the leaf 9 is compressed or extended in accordance with the force applied to the instrument. 85 90 95

In Fig. 4 the flexible member is shown as provided with a mouth piece or grip 12 at its free end which is placed between the upper lip and the upper teeth. The vibrator or leaf may be formed of any suitable flexible 100 material or metal.

My flexible member is readily applied to existing forms of mouth pieces and the instrument can be played and the various tones produced without the usual fatigue to the 105 player.

What I claim is:

1. In a mouth piece for wind instruments, the combination of a cup-shaped member, and a flexible leaf secured at one end in the 110 cup-shaped member and extending lengthwise of the mouth piece beyond the entrance

thereof, the leaf dividing the cavity of the mouth piece into upper and lower sections, substantially as and for the purpose described.

- 5 2. In a mouth piece for wind instruments, the combination of a cup-shaped member, and a flexible leaf secured at one end in the cup-shaped member and extending lengthwise of the mouth piece beyond the entrance thereof, the leaf dividing the cavity of the mouth piece into upper and lower sections, the free end of the leaf being movable inwardly toward the upper side of the entrance of the mouth piece, substantially as and for the purpose specified.
- 10 3. In a mouth piece for wind instruments, the combination of a cup-shaped member, and a flexible leaf secured at one end in the cup-shaped member and extending lengthwise of the mouth piece beyond the entrance thereof, the leaf being located in the upper half of the cavity of the mouth piece and having its free end carried inwardly and normally spaced apart from the upper side of the entrance of the mouth piece and movable during flexing of the leaf toward and from said upper side, substantially as and for the purpose set forth.
- 15 4. In a mouth piece for wind instruments, the combination of a cup-shaped member and a flexible and endwisely compressible leaf secured at one end in the cup-shaped member and extending lengthwise of the mouth piece beyond the entrance thereof, and curving upwardly toward its outer free end, substantially as and for the purpose specified.

- 20 5. In a mouth piece for wind instruments, the combination of a cup-shaped member and a flexible endwisely compressible leaf secured at its inner end in the cup-shaped member and formed with transverse folds or bellows to make the same endwisely compressible, the leaf extending lengthwise of the mouth piece beyond the entrance thereof and curving upwardly toward its free outer end, substantially as and for the purpose set forth.
- 25 6. In a mouth piece for wind instruments, the combination of a cup-shaped member having a passage leading from its inner end, and a leaf having a tubular hollow plug inserted in said passage and located at a point remote from the entrance of the mouth piece, and a leaf extending from the plug lengthwise of the mouth piece toward the entrance of the mouth piece, substantially as and for the purpose described.

In testimony whereof I have hereunto signed my name, at Syracuse, in the county of Onondaga, and State of New York, this 6th day of May, 1919.

CHARLES O. WIDMAYER.
